UNITED STATES PATENT OFFICE

2,503,955

CONVOLVED TRANSMISSION LINE

Nils E. Lindenblad, Rocky Point, N. Y., assignor
to Radio Corporation of America, a corporation
of Delaware

Application September 24, 1942, Serial No. 459,497

1 Claim. (Cl. 178—44)

1

The present invention relates to electrical circuits having characteristics similar to those of transmission lines.

An object of the present invention is the provision of an artificial line having uniformly distributed characteristics.

Another object of the present invention is the provision of an artificial line which is compact in size.

Still another object of the present invention is the provision of an artificial line having characteristics which do not vary with changes in the frequency of energy applied thereto.

A further object of the present invention is the provision of an artificial line which has a phase shift characteristic which is linear with respect to frequency.

Still a further object of the present invention is the provision of a compact artificial line which, in spite of its size, will handle large amounts of energy.

The foregoing objects, and others which may appear from the following detailed description, are attained in accordance with the principles of the present invention by so convolving coiling or folding a natural line that it occupies a small space without at the same time introducing such mutual inductive effects, either electrostatic or electromagnetic, between different convolutions or layers of the coiled line that it ceases to act as a natural line. It is to be understood that in convolving the conductor of the end line, the line may be wound or twisted either upon itself or wrapped about another object, or it may be folded back and forth on itself or with relation to another object.

The present invention will be more fully understood by reference to the following detailed description, which is accompanied by a drawing in which Figure 1 illustrates an embodiment of the invention, while Figures 2 and 3 illustrate a portion of the modification thereof in front and side views, while Figures 4 and 5 illustrate in elevation, partly in section, and in plan, a further modification of the invention and Figures 6 and 7 illustrate further modifications of the invention.

Referring, now, to Figure 1, reference numeral 10 indicates a conductive tube carrying a plurality of insulating rods 11 around the outside of the tube. The purpose of insulating rods 11 is to act as a spacing support for coiled line 12 which is space wound about the outside of the rods. The coiled line 12, together with the supporting tube 10, is supported within an outer metal cas-

2

ing 14 which is hermetically sealed at each end by end plates 16 and 17. Tube 10 may be supported in position within casing 14 by being rigidly attached at one end to plate 16. At the other end tube 10 passes through a supporting plate 15 which is secured within casing 14. The ends of the line 12 are connected to terminals 18 and 19 carried by insulator bushings 20 and 21 secured in a side wall of casing 14. End plate 17 is preferably provided with a pressure gauge 22 and an inlet valve 24 by means of which a predetermined pressure of gas may be maintained within the casing 14. Tube 10 fits within the central aperture in plate 15 loosely enough that the gas within the casing may flow by the plate. Apertures such as at 15' may be provided in the plate if it is deemed necessary. Due to the comparatively small spacing of the convolutions of line 12 from the supporting tube 10 and the outer casing 14, the mutual effects between adjacent turns or convolutions of coil 12 are so reduced that the line acts substantially the same as though it were straight instead of being coiled up.

The modification shown in Figures 2 and 3 utilizes a plurality of metal plates 26, 27 and 28, the coiled line conductor 12 being supported by plate 27 and surrounded by plates 26 and 28 whereby the adjacent portions are shielded one from the other. The central plate 27 carries on opposite edges insulating support strips 30 and 31 upon which the convolutions of coil 12 are wound. The plates are maintained in a parallel relationship by suitably arranged bolts 25 and spacers 25'. Due to the close spacing of the successive convolutions of coil 12 from the metal plates 26, 27 and 28, the mutual effects therebetween are so reduced that the line acts as though it were a straight line.

The requisite number of units as shown in Figures 2 and 3 to obtain a desired line length may be connected in series and placed in a liquid tight casing filled with transformer oil. Thus the current carrying capacity of the line is somewhat improved due to better cooling and, also, the successive convolutions of the line are additionally insulated one from the other.

The further modifications shown in Figures 4 and 5, like that of Figures 2 and 3, utilizes a plurality of separate line sections each of which may be supported within a shield 32. The sections are connected in series and placed within a conductive container 34 which is filled with transformer oil. The container may be covered by an insulating top 35 which carries a terminal 36 to which one end of the line is connected, the

other end being connected to the container 34. Each line section, in this modification, is constructed by first winding the conductor upon a small diameter mandrel to form an elongated helix, the successive turns of the helix being slightly spaced one from the other. The helix, after being removed from the mandrel is then space wound upon an insulating support 37 which may be a glass tube or rod. The support 37 may be threaded to hold the turns in place or they may be cemented to the support by coating them with shellac or other cement. The shields 32 are preferably welded or soldered together into a honeycomb-like arrangement with combined spacing fins and supporting legs 38 attached to the periphery to maintain the desired relationship between the shields, the casing and the coils.

The further modification of the present invention shown in Figures 6 and 7 is of particular advantage when artificial lines of low characteristic impedance are desired. In the exploded view of Figure 6 is shown the conductor 42 in the form of a long flat ribbon folded back and forth in a zig-zag manner. On each side of the ribbon 42 is placed a long insulating strip 43.

If desired, the ribbon may be wound with insulating material in the same way as magnet wire is insulated, or an insulating sleeving woven over the ribbon. It is so shown in Figure 7. Into each of the bends of the zig-zag ribbon is inserted a metallic ground plate 47 similar in form to that shown in Figure 2 in plan. The grounded plates 47 are then pressed closely together and secured in position by means of securing bolts 25.

While I have particularly shown and described several modifications of the present invention, it should be clearly understood that the invention is not limited to these forms alone, but that modifications may be made.

I claim:

An artificial line including an elongated inner conductive tube, a plurality of thin insulating strips arranged about said conductive tube parallel to the axis of said tube and an elongated conductor wound in a spaced relationship over said insulating strips, an outer conductive tube closely surrounding said inner conductive tube and arranged in coaxial relationship therewith, the spacing between said conductive tubes and said conductor being small substantially to decouple successive turns of the winding of said conductor one from the other, said outer conductive tube being sealed fluid tight, and means for maintaining an insulating fluid under pressure within said outer conductive tube, the spacing between said conductive tubes being maintained by annular discs interposed between said tubes at each end of the winding on said inner conductive tube.

NILS E. LINDENBLAD.
